UNITED STATES PATENT OFFICE.

JOSEPH W. DOUGLAS, OF MIDDLETOWN, CONNECTICUT, ASSIGNOR TO W. AND B. DOUGLAS, OF SAME PLACE.

DESIGN FOR PUMP-BARRELS.

Specification forming part of Design No. 6,032, dated August 20, 1872.

Specification describing a Design for Pump-Barrels, the invention of JOSEPH W. DOUGLAS, of Middletown, in the county of Middlesex and State of Connecticut.

The nature of this design is fully represented in the accompanying drawing, to which reference is made.

At the base of the pump-barrel is a plain flange, *a*, for securing it to its support. Above this there is a compound double-cyma molding, *b*, embellished with figures whose configuration is clearly represented. Immediately above the molding *b* is an ogee molding, *d*, above which is a cavetto, *f*. Above this the barrel is cylindrical for some distance, as shown at *g i*, and this cylindrical portion is surrounded by an ornamented bead, *h*, and a fillet. The said portion *i* has above it another bead, *j*, ornamented like the one *h*, and, like it, having a fillet on each side of it. Surmounting this head is an upwardly-flaring portion, *k*, which is separated from the main portion *l* of the pump-barrel only by a narrow cavetto, *m*, in the lower edge of the latter, and is ornamented with upright ribs *n n*.

The main portion *m*, which is cylindrical, is ornamented with adjoining figures *o o*, whose shape is clearly shown. The spout of the pump has a bead, *p*, at its mouth, and at its junction with the portion *l* there is a foliate figure, *q*. In the upper edge of the said portion *l* there is a cavetto, *r*, and above this is a cable-like bead, *v*. This bead is surmounted by a fillet having above it a cylindrical portion, *s*, paneled as shown at *t t*. A twisted bead, *u*, similar to the bead *v*, surmounts this portion *s*, and is bounded on each side with a narrow fillet. Above this is a narrow band surmounted by a cavetto, *w*, and topped by an ovolo, *x*, from which project on one side the bearings *y y* for the pump-handle, and on the other a lug, *z*, for the reception of a bolt.

What I claim as my invention, and desire to secure by Letters Patent, is—

The design for a pump-barrel, substantially as shown and described.

JOS. W. DOUGLAS.
